TELEPHONE TOLL APPARATUS

George A. Long, Hartford, Conn., assignor to The
Gray Telephone Pay Station Company, Hartford,
Conn., a corporation of Connecticut

Application May 13, 1933, Serial No. 670,928

3 Claims. (Cl. 179—6.3)

My invention relates to the class of devices above named, and an object of my invention, among others, is the production of means in a telephone of the so-called "French" or monophone type whereby maximum results may be obtained in its use.

One form of a telephone apparatus embodying my invention and in the construction and use of which the objects herein set out, as well as others, may be attained is illustrated in the accompanying drawing in which—

Figure 1 is a front view of a telephone apparatus embodying my invention.

Figure 2 is a side view of the same with parts broken away to show construction.

Figure 3 is a rear view of the front case illustrating a portion of the mechanism for depositing of coins.

Figure 4 is a diagrammatic view illustrating the wiring embodied in my improved telephone toll apparatus.

The great popularity of the so-called "French" or monophone type of telephone which exists at the present time has created a demand for use of this type of telephone in connection with telephone toll collecting apparatus, and, moreover, this type of telephone is found to possess distinct advantages over that type in which the transmitter is placed in a fixed position, as the monophone type may be conveniently used in any desired position by the person speaking, thereby enabling such person to assume an easy and natural posture during conversation and not requiring him to assume a strained, unnatural and tiresome position in a manner frequently compelled by telephones having the fixed form of transmitter.

In the pay station apparatus which is being displaced by this later type of telephone the transmitter on the front of the case serves the dual purpose of picking up the voice vibrations from the air and the coin actuated signals through the direct resonant connections in the steel cover or case with the transmitter circuit which enables the operator at the central office to aurally determine whether the required toll for the use of the apparatus has been deposited, through the use of a single transmitter as above described. With this so-called "French" type of telephone the transmitter being embodied in the hand set which is removed from the telephone case when in use is not in direct resonant connection with the sound signals, and these signals have insufficient volume to be picked up by air vibrations. I have therefore made use of a second transmitter to pick up the sound signals, preferably through a

resonant connection with the bell and gong, and have devised means whereby the signals created by the coin may be transmitted over the talking circuit.

Such apparatus embodying my improvement is illustrated in the drawing herein in which the numeral 5 denotes the back of a coin controlled telephone set, 6 the upper portion of the enclosing case, 7 the lower portion of such case, 8 a coin gage plate to receive and direct coins to a channel plate 14. A dial 9 is supported on the upper section of the case and a supporting hook 10 projects from the side of said case to receive a hand set 11. A coin return opening 12 is formed in the lower portion of the case, all of the parts just described being common to telephone toll collecting apparatus now in general use. This apparatus also includes a coin receptacle 13 in the form of a drawer removably secured in the lower section 1 of the case and into which coins or other tokens paid for the use of the instrument pass from the coin gage plate 8 through the channel plate 14 having channels 15 for guiding coins of different denominations against signals, as a bell 16 and a gong 17 in a manner that will be readily understood by those skilled in the art and for which reason a more detailed description and illustration are omitted herein.

In the adaptation of my invention I place in resonant connection with the sound signal devices, as the bell 16 and gong 17, a coin signal pick-up transmitter 18. This may be arranged in various ways, one of many contemplated by me being to place this transmitter 18 within the case, which is constructed of metal, the sounding signals also being secured in firm contact with said case, thereby establishing a resonant connection between said signals and the transmitter.

The sound of the signals picked up by this transmitter may be conveyed to the central station operator in various ways. In the device illustrated herein and which satisfactorily accomplishes my purpose I connect the transmitter 18 in series with the monophone transmitter, and by a wire 19 which is connected on opposite sides of the transmitter and as shown in Fig. 4 of the drawing. This introduces a resistance into the line, and if this shall be found objectionable I may make use of a shunted resistor 20, thereby reducing the line resistance for voice transmission if desired and also reducing the sensitivity of such transmitter to extraneous noises. The resistor has a capacity of substantially seventy-five ohms which satisfactorily answers my purpose.

While this reduces the strength of the sound signals, the resonant connection of the signals with the transmitter is so effective that the audibility of the signals to the operator is clear.

5 In the wiring diagram illustrated in Fig. 4 much is shown that does not require detailed description, as it will be readily understood by those skilled in the art. Briefly set out the numeral 22 denotes a receiver switch, 23 a ringer, 10 24 a condenser, 25 a polarized coin relay, 26 a ground switch closed by the action of coins, and 27 a calling device of the dial type, all of which are common to telephone apparatus now in general use.

15 In the operation of the telephone pay station herein described the circuit functions in the usual manner for incoming calls except that the coin signal pick-up transmitter and its resistor are connected in series with the monophone trans- 20 mitter.

For local calls the subscriber lifts the monophone from the hook but he does not hear the dial tone and cannot dial without depositing a coin. When a coin is deposited it closes the ground switch 26 which connects one side of the line to the ground in series with the polarized coin relay 25. This effects a ground relay to operate at the central office and it also unlocks the pay station trunk for dialing. The subscriber 30 may now dial his party in the usual manner. One pair of the off-normal springs in the calling dial 27 breaks the receiver circuit and the other pair of said springs shunts both the monophone transmitter and the coin signal pick-up trans- 35 mitter so that there is a clear path of no resistance for the dial impulses. Conversation can proceed in the usual manner except that the coin signal pick-up transmitter and its shunting resistor are in series with the monophone trans- 40 mitter.

For toll calls the subscriber calls the operator as before for a local call and the operator requests the deposit of the charge, the deposited coin striking gongs or bells according to their

denominations. These sound signals are set in vibration which are carried through resonant connection to the coin signal pick-up transmitter 18 and thence out on the line to the operator. If the proper charge has been deposited the operator completes the connection. Upon completion of the conversation the operator collects the charge held in suspense in the coin hopper 28 by pressing a key which applies a high voltage to the polarized coin relay 25 to the ground. If 10 the call is not completed the operator refunds the charge by pressing a key which applies a high voltage of opposite polarity through said polarized relay to the ground.

I claim:

1. The combination in a telephone including a transmitter for voice transmission, a plurality of sound signals for denoting payment for use of the telephone, and a single base of resonant material upon which all of said signals are mounted, 20 of a second transmitter mounted on said single base separate and apart from said signals with the single second named transmitter in resonant connection with all of said sound signals to transmit the sounds thereof. 25

2. The combination in a telephone including a transmitter for voice transmission and sound signals for denoting payment for use of the telephone, of a second transmitter in resonant connection with all of said sound signals and a circuit for conveying said sound and voice signals, said circuit including a shunt resistor around said second transmitter. 30

3. The combination in a telephone including sound signals for denoting payment for use of the telephone, a single metallic element for the support of the signals, of a transmitter for voice transmission in non-resonant connection with said sound signals, and a second transmitter mounted separate and apart from said signals 40 and upon the metallic element and in resonant connection with the signals for transmission of the sounds thereof. 45

GEORGE A. LONG.
